UNITED STATES PATENT OFFICE.

WILLIAM McCLOVE, OF SCRANTON, PENNSYLVANIA, ASSIGNOR TO
McCLOVE-BROOKS COMPANY, A CORPORATION OF PENNSYLVANIA.

STOKING-GRAVE MECHANISM.

No. 881,177.

Specification of Letters Patent.

Patented Sept. 18, 1906.

Application filed August 4, 1905. Serial No. 272,705.

To all whom it may concern:

Be it known that I, WILLIAM McCLOVE, a citizen of the United States, residing at Scranton, in the county of Lackawanna and State of Pennsylvania, have invented certain new and useful Improvements in Stoking-Grate Mechanism; and I do hereby declare the following to be a full, clear, and exact description of the invention, such as will enable others skilled in the art to which it appertains to make and use the same.

This invention relates to improvements in stoking-grate mechanisms for furnaces; and it is the object of the invention to provide a grate-surface which is so constructed that small or fine fuels, as well as the larger fuels, may be used thereon and gradually fed down the grate-surface, the bars of the grate being moved at suitable periods or intervals or continuously, if desired, to lift and push the fuel at a proper speed toward the lower end of the grate.

With these and other objects in view the invention comprises certain novel constructions, combinations, and arrangements of parts, as will be hereinafter fully described and claimed.

In the accompanying drawings, Figures 1 and 1^a are vertical sectional views of a grate mechanism constructed in accordance with the present invention, Fig. 1^a being a continuation of Fig. 1 upon a second sheet. Fig. 2 is an enlarged sectional view through a portion of the said grate mechanism, showing some of the bars of the grate-surface and the intermediate space-filling bars. Fig. 3 is a similar view, but showing one of the bars in its upwardly-rocked position, as when lifting and feeding the coal down the grate-surface. Fig. 4 is a top plan view of a portion of the grate-surface looking at the same as if its upper surface occupied a horizontal plane. Fig. 5 is an elevation of a portion of one of the space-filling bars at the upper edge of the grate adjacent to the inner edge of the dead-plate. Fig. 6 is a rear elevation of a portion of one of the intermediate filler-bars mounted between the movable grate-bars of the grate. Fig. 7 is a similar view of one of the rocking or movable grate-bars. Fig. 8 is a transverse sectional view of the grate mechanism, showing the same made up of three grate-sections and illustrating the manner of mak-

ing the bars of the sections move simultaneously. Fig. 9 is a detail end elevation of one of the rocking grate-bars without caps. Fig. 10 is a detail cross-sectional view through the body portion of a rocking grate-bar and looking toward one of the lugs by which the bars of different grate-sections are joined. Fig. 11 is a sectional view similar to Fig. 1, but showing the means for securing a differential movement in the rocking of the grate-bars secured to the furnace-front. Fig. 12 is a detail sectional view through a portion of the grate mechanism, showing a slightly-modified form of some of the intermediate caps of the grate-surface. Fig. 13 is a detail view showing an end elevation of the supporting-webs for the intermediate caps. Fig. 14 is a detail view showing a modified manner of supporting the connecting-pins for the bars of the grate-sections.

The grate mechanism forming the subject-matter of this invention is so constructed that a grate-surface of moderate inclination may be used for handling and causing the proper consumption of fine fuels, and especially the exceedingly fine anthracite fuels which it has been difficult heretofore to use in furnaces.

The grate-surface is so constructed that such fine fuels may be fed down the inclined surface thereof without the necessity of making the incline of such surface exceedingly steep, and the said grate-surface is also so constructed that the fine fuels employed cannot run through the grate-surface into the ash or forced draft-pit below.

I have illustrated in the accompanying drawings the preferable form for manufacturing the grate in carrying out the purpose of the present invention, and in such a grate there are employed two or more carrier-bars, as 1 and 2, upon the upper edge of which are movably mounted the various bars and fuel-supporting surfaces which make up the stoking-grate mechanism.

In the drawings I have designated the intermediate carrier-bars by the numeral 1, while I have applied the numeral 2 to the outer or extreme side carrier bars on the edge of the grate-surface. Of course it should be clearly understood that the number of sections in the grate-surface is not material to the invention, since one section may be employed or a plurality, in accordance with the size of

the furnace and the work which is required of it. Of course when there is only one section in the grate-surface the two carrier-bars necessary therefor would be made like the 5 outer carrier-bars 2, but when a plurality of grate-surfaces is embraced within the grate-surface the intermediate bars are made like those indicated by the numeral 1.

The carrier-bars are supported in the furnace structure in any desired manner, their 10 front ends resting upon supports or ledges 3, formed upon the inner face of the furnace-front 4, while the rear ends rest upon bearer bars or plates 5, mounted in the bridge-wall 15 of the furnace. The upper edges of the carrier-bars 1 and 2 are provided at intervals with recesses or sockets forming journal-bearings 6 for receiving the stoking-grate bars. The portions of the carrier-bars between the 20 journals 6 are preferably lowered, so as to fall away from proximity to the heat generated upon the furnace-surface. In this manner the greater portion of the carrier-bars are separated from the intense heat on the grate-surface by considerable space, and all tendency 25 of warping or bending the carrier-bars is thereby decreased.

Extending across the grate-surface and reaching from one carrier-bar to the other is 30 a plurality of movable or rocking fuel-engaging bars 7, and these bars have journals or trunnions 8 at each end which are adapted to fit into and find a bearing upon the journal-bearings 6 of the carrier-bars.

35 Each of the movable grate-bars 7 is made up of a body portion having a series of elongated sockets 9, formed therein, and the said body portions are formed with inwardly-turned cap-engaging edges 10 and 11 at their 40 upper edges and 12 and 13 at their lower edges for engaging the shanks of the fuel-stoking caps, which will be hereinafter fully described. Extending below the socketed body portion of each bar is a rod or bar 14, which is connected at intervals by curved 45 hangers 15 with the body portion of the bar. These rods or bars 14 are adapted to be engaged by the ends of bar-rocking rods 16. The said rods extend forward in the grate 50 mechanism and engage actuating means mounted in the front part of the furnace structure for communicating a proper movement to the grate-bars in feeding the fuel down the inclined grate-surface.

55 The fuel-engaging and stoking portions of the said rocking grate-bars are made up of a series of caps 17, each of which is provided with a main stem 18, the said stem extending from the top or fuel-engaging portion of the 60 cap downwardly to a point below the fuel-supporting portion of the cap, the lower portion of the stem being reduced in size and tapered to form socket-engaging shanks 19.

The said shanks have a continuous taper in 65 cross-section from top to bottom, as shown in

Fig. 2, and are made of considerable width in front elevation, as shown in Fig. 7, the lower portions of said shanks being reduced in width, as clearly indicated in dotted lines in said Fig. 7. Extending upon opposite sides 70 of the central stem 18 of each cap is a series of parallel webs 20 and 21, forming fuel-supporting fingers with air-spaces between them. The front ends of the said webs or fingers 20 are connected by a curved tie-plate 22, the 75 outer surface of which is curved, having the axis of the movement of the grate-bar as a center.

The fuel-supporting webs or fingers 20 are made of considerable length, so as to fill the 80 space between the stem portions of the caps and the adjacent bars of the grate-surface. The webs or fingers 21, which project in an opposite direction from the webs or fingers 20, are preferably not connected or tied at 85 their outer edges like the fingers or webs 20, and the said fingers or webs 21 are made comparatively short, as clearly illustrated in Figs. 1, 1^a, 2, 3, and 4 of the drawings. The upper and rear edges of the webs or fingers 90 21 are preferably curved, their curved edges being struck from the center of movement of the grate-bar as a center, and because of such concentricity the rocking movement of the 95 grate-bars will not operate to move the intermediate or filler bars mounted between the adjacent rocking bars.

A small space is left between the forward edges of the fingers on the upper rocking grate-bar and the rear edge of the dead-plate 100 23, and in order to fill this space and prevent the running through of fine fuels at this point a movable filler-bar or cap 27 is employed. A fixed transverse lower bar 24 is positioned below the filler-bar 27 for supporting the same and extends from one carrier-bar to the other and is rigidly secured at its ends thereto. Each end of said fixed bar 24 is provided with downwardly-turned lugs or flanges 25, and a securing-bolt 26 is passed 105 through each of said lugs and the carrier-bar adjacent thereto. Upon the upper portion of said bar is mounted a movable fuel-engaging surface made up of a series of apertured bars or caps 27, which caps are preferably of 110 the same width as the caps of the rocking grate-bars. These caps 27 are formed with downwardly-projecting lugs 28, clearly shown in Figs. 2 and 5, and the said lugs are pivotally connected by pivot-pins 29 with 115 upwardly-extending lugs or standards 30, formed upon the fixed bars 24. The said fixed bars 24, supporting the filler-bars 27, are inclined with respect to the grate-surface, so that the pivoted bars or caps 27 rest normally against the curved surfaces of the tie-plates 22 upon the adjacent rocking bars, and the space between said bars is thus always filled. Although the edge of the caps 27, which rest against the tie-plates 29, may 120

be made of solid material, I preferably form a series of recesses or parallel meshes 31 therein so as to lessen the friction between the caps and the tie-plates 22 at this point. Such meshes also permit of the passage of some air between the adjacent caps of the bars and reduce the temperature which might be otherwise attained at this point.

The intermediate filler-bars arranged between the adjacent rocking bars of the grate-surface are preferably made up of fixed angle-bar portions 32, bolted to the carrier-bars by bolts 33 and movable top or fuel-engaging caps 34 and 35. The caps 34 and 35 are also made, preferably, of widths corresponding with the width of the movable grate-bar caps 17. Of these movable caps for the intermediate filler-bars the largest, 34, almost fill the space between one movable or rocking bar and the adjacent one, and the caps 35 are comparatively small, being sufficient only to bridge the space between the lower edges of the large caps 34 and the caps 17 of the next movable bar.

In order to properly support the movable caps 34 and 35, upwardly-projecting webs 36 are provided at suitable intervals upon the upper edge of the fixed bar portion 32 and downwardly-extending lugs 37 on the caps 34, and lugs 38 on the caps 35 are pivotally connected with the said webs 36 by pivot-pins 39 and 40. The pivot-pins 39 of the caps 34 are situated at points so nearly beneath the rear edges of the said caps 34 that their forward edges fall under the action of gravity toward the rear edges of the webs 21, projecting from the caps 17 of the movable bars. The body portion of each cap 34 is made up of a series of downwardly-tapering webs or fingers 41, which are joined at the forward edge of the cap by tie portions 42, which tie portions closely fit the edges of the webs 21. The rear of the said fingers or webs 41 are also joined or tied by a tie portion 43, arranged either at the rear edges of the fingers or near the same. The said rear edges of the said fingers project rearwardly over the forward portions of the adjacent caps 35.

In using very fine fuels it is important to so form and mount the caps 34 that there shall be practically no space between the forward edge of the said caps and the edges of the webs 21 on the adjacent bars. To insure a proper fitting of these parts, the caps 34, when first newly mounted in the grate structure, are permitted to rest upon the webs 21, and means is provided for arresting the wear between the parts after a worn or practically ground joint is formed, where they touch. The means employed for arresting such wear comprises stops or detents 64, formed upon the cap-supporting webs 36 of the fixed bars 32. This structure is clearly illustrated in Figs. 12 and 13, in which it will be noticed that the webs 36 extend forwardly beneath

the caps 34, as at 63, and carry at their forward ends the detents 64. The detents 64 project laterally from the webs 36, so as to lie beneath the webs 37 of the caps 34. In this structure the said webs 37 are shouldered at 65, so as to provide a projection capable of resting upon the detents 64. It will be readily understood that after the forward edges of the caps 34 are worn sufficiently in their engagement with the webs 21 to permit the shoulders 65 to engage the detents 64 there will be no further wear upon the parts.

I do not wish to be understood as limiting myself to the use of the detents 64, as the caps may be formed without such detents, as illustrated in Figs. 2 and 3 of the drawings, the weight of the caps holding them against the webs 21 of the adjacent rocking bars.

The caps 35 are provided with transverse body portions which are made comparatively small in cross-section, and from the forward edges of these body portions project a series of downwardly-tapering fingers or webs 44, which project beneath the overhanging rear edges of the caps 34. The under or rear edge of the said caps 35 are meshed, as at 45, so that air-spaces are left between the said caps 35 and the adjacent curved tie-plates 22 of the rocking grate-bars, against which the said caps rest. The fixed body portion 32 of each intermediate filler-bar is preferably formed with a tapered end portion 46, as clearly seen in Fig. 4, which fits into a corresponding tapered recess or socket 47, formed in a projection 48, extending upwardly from the body portion of each carrier-bar. The securing bolts or pins 33 are passed through laterally-projecting lugs 49, formed on the ends of the said fixed bar 32. The tapered end projections 46 of the said bars prevent the tipping thereof, while the pins 33 lock the bars against vertical displacement. The movable caps 34 and 35 practically seal the spaces between the adjacent movable bars. This construction permits of the feeding of very fine fuels down the surface of the grate without the chance of the same running through the grate-surface and escaping consumption. The rear ends of the caps 34 are generally made to project slightly above the normal level of the grate-surface, as indicated in Fig. 2, and thus tend to prevent the rapid running of the fuel down the grate-surface, especially when the fuel is being positively fed down the said surface by the rocking of the movable grate-bars. The said pivoted caps 34 may, however, be made level with the surface of the grate or may be made to project to a greater distance above the said level than shown in Fig. 2 without departing in the least from the spirit of the invention. The lower end of the grate-surface is preferably completed by a fixed tie-bar 50, which extends from one carrier-bar to the other, securing them fixedly with respect to each

other. Below the tie-bar 50 I usually mount a rocking cut-out bar 51, which is so constructed as to be capable of cutting out ashes and clinkers at intervals and dumping them 5 into the ash-pit below the grate. The said tie-bar and the said rocking cut-out bar may be of any desired construction, and since these bars form no material part of the present invention it is not deemed necessary to 10 specifically describe the same.

Returning now to the rocking grate-bars, which form an important feature of this invention, it should be pointed out that since the greater portion of the caps 17 project forwardly from the body portions of the bars and the greatest weight supported by the bars is thus carried by the forward wall at its upper edge and the rear wall at its lower edge the said forward wall is extended above the 20 upper edge 11 of the rear wall. The upper edge of the said forward wall thus forms a strong abutment for lifting the weight resting upon the overhanging portion of the caps 17 and forces upwardly and backwardly the fuel which is engaged by the rocking bars. The lower rear edge of the rocking bars are 25 also thickened and strengthened, as clearly illustrated in the sectional views in Figs. 1, 1^a, 2, and 3.

30 As shown in Fig. 7, the journals 8 project beyond the end of the body portion of the rocking grate-bars, and the end caps of the rocking bars are preferably made to project beyond the said journals and overhang the same, as well as a part of the space over the carrier-bar. As shown in Fig. 7, the end cap upon the bar is made wider than the intermediate caps, and the under side of the outer edge of said cap is reduced in depth, as at 53, 40 so as to accommodate the journal 8. Where the end caps overhang the intermediate carrier-bars 1, (shown in Fig. 8,) the said end caps of said bars approach each other, so as to leave only a slight space, preferably equal 45 to that between the adjacent caps on the intermediate portions of the bars. Where the said end caps overhang the outer carrier-bars 2 of a grate-surface, the caps approach the side walls of the furnace, so as to leave only 50 a slight space, preferably about that equal to the space between the intermediate caps on the bars. In this manner the journals of the bars are thoroughly protected by the end caps of the said bars, and no greater spaces 55 are formed between the grate-sections than between the adjacent intermediate caps of the grate-bars.

As shown in Figs. 1 and 1^a the grate-bars, which are movably mounted and which are 60 used for stoking or feeding fuel down the grate-surface, are connected by the rods 16 with operating mechanism at the front of the furnace. The operating mechanism, as shown in said figures, may be made up of pivoted 65 levers 54, mounted inside the furnace-front

and connected by means of rods 55 with differential actuating means 56, mounted outside the furnace-front and capable of imparting movement to a greater or less extent, according to the adjustment, to the rocking 70 bars inside the furnace. The structure thus illustrated is preferably like that shown and described by me in my Patent No. 689,827 and needs no special description at this point. As shown in Fig. 11, the movable grate-bars 75 may, however, be operated by a differential feeding mechanism, which is located inside the furnace-front, as at 57, and which is constructed like the mechanism shown and described in my Patent No. 622,517. Of course 80 it will be evident that any desired rocking mechanism may be employed for actuating the fuel-feeding bars of the furnace without departing from the spirit of the invention in the least.

As heretofore intimated, the grate-surface may be made up of a single grate-section or a plurality of grate-sections. When the grate-surface is made up of a plurality of grate-sections—say, for instance, three, as shown in 90 Fig. 8—it is only necessary to impart movement directly to one of said grate-sections, for the movement thus imparted thereto can be further imparted to the adjacent grate-sections in a simple method and by simple 95 means, which will now be described. One of the grate-sections—as, for instance, the intermediate section—may be provided with downwardly-projecting lugs 58, which project below the engaging rod 14 and which are perforated, so that a bolt may be passed through said perforations. The adjacent 100 grate-sections have one or more of their bars provided with a similar projecting lug, as 59, which is also perforated, and a connecting 105 bolt 60 is passed through the apertured lug 59 and thence through a slot 61, formed in the intermediate carrier-bar 1, the bolt then passing through the apertures in the lugs 58. The inner end of said bolt may be engaged 110 by any suitable locking means, a cotter-pin 62 being shown in Fig. 8 for holding such bolt in place. The slot 61 in the carrier-bar is made concentric with the center of movement of the grate-bars which carry the lugs 115 58 and 59, so that the said bars may be rocked and the pin or pins 60 carried therewith. It is necessary to provide a connecting-pin 60 for each of the adjacent grate-sections, so that any movement imparted to the 120 various bars of the central section will likewise be communicated to the individual bars of the adjacent connected sections. By providing two lugs 58 on one of the bars a sufficient rigidity is given to the pin 60 to move 125 the adjacent bar positively in exact accordance with the bar carrying the said lugs. Of course a greater or less number of lugs may be employed, if desired, without departing from the spirit of the invention. By the use 130

of these connecting-pins and lugs it is only necessary to impart movement directly to the bars of a single grate-section in order to operate all the bars of the whole grate-surface in proper correspondence with each other.

Instead of placing the pins 60 near the lower ends of the lugs 58 the said pins can of course be passed through the ends of the bars at higher points, and the said pins may be passed through the lugs which carry the rods or bars 14 without departing from the spirit of the invention. Where the ends of the grate-bars bridge the outer carrier-bars 2, the said carrier-bars are also provided with slots 66, similar to the slots 61, and short pins 67 are secured to the adjacent ends of the bars, the said pins 67 serving to prevent the rising of the bars from their journal-bearings.

20 In employing a stoking-grate surface like that above described the plane of the grate-surface is arranged usually with an incline of about twenty-five degrees. The fine fuels are fed upon the upper end of the grate-surface from the fuel-feeding hopper in any desired manner, and the rocking grate-bars are then given a movement at suitable intervals to tip their forward edges upwardly, as shown in Fig. 3, and thus force the fuel down the grate-surface. The mechanism which operates the rocking grate-bars can, as described in my previous patents referred to, be made to impart a slow movement or a rapid movement to the rocking grate-bars, as found needful or desirable in feeding the burning fuels down the grate-surface. Because of the lifting and downwardly-forcing power of the rocking bars claimed in the present invention the incline of the grate can be made less than is generally required in stoking-grates of a similar character to that described in the present invention.

By the construction of the grate the fixed portions of the carrier-bars and of the grate-bars are dropped to a considerable distance below the fuel-bearing surface of the grate-caps and are thus protected from the extreme degrees of heat generated in the firebox of the furnace. Although the filler-bars employed for closing the spaces between the movable bars are so formed that the fuel cannot run through between any of the arms, yet ample air-space is afforded between adjacent bars by the arrangement of the webs or fingers for sufficient draft to reach the burning fuel and also for so distributing the air which passes through the grate-surface that the parts in contact with the burning fuels are protected in a large degree from extreme heat and are maintained at a reasonably cool temperature. The life of the grate-bars is thus greatly increased over what it would be were the bars made of a more solid construction and less open to the influence of the air.

Having thus fully described my invention, what I claim as new, and desire to secure by Letters Patent, is—

1. An inclined stoking-grate mechanism, comprising a series of spaced movable grate-bars, a series of filler-bars for sealing the spaces between them against the running through of fuel and forming a substantially continuous surface, and means for supporting the parts in proper relative position. 75

2. A stoking-grate surface comprising a series of spaced movable grate-bars, and a series of movable filler-bars on the same plane as the grate-bars resting against the movable grate-bars, the said movable filler-bars forming the sole fuel-supporting means between the movable grate-bars. 85

3. A stoking-grate surface, comprising carrier-bars, rocking grate-bars journaled thereon, and filler-bars interposed between the rocking bars and having movable fuel-supporting caps for movably engaging the said rocking bars. 85

4. A stoking-grate surface, comprising a plurality of rocking grate-bars and filler grate-bars mounted between them having rigid supporting portions and cap portions pivotally mounted on the supporting portions for filling the space between the said bars said cap portions in operation contacting with 95 said rocking grate-bars.

5. A stoking-grate surface, comprising a plurality of rocking fuel-feeding bars, a plurality of filler-bars mounted between them having cap portions pivotally mounted on 100 the supporting portions, the cap portions resting against adjacent fuel-feeding bars through the action of gravity for sealing the spaces between the bars and preventing fuels from running through the grate-surface. 105

6. A stoking-grate, comprising a plurality of rocking grate-bars having fuel-stoking portions extending well to one side of the body portion of the bars, intermediate space-filling bars mounted between the rocking bars and normally impinge against said rocking bars, and means for rocking the said bars so as to lift the fuel-stoking portions thereof and force the said fuel down the grate-surface. 110

7. A fuel-stoking grate, comprising carrier-bars, rocking bars journaled thereon having caps formed with curved surfaces, concentric with the respective axes of movement of the bars, and filler-bars in the same plane as said rocking bars arranged in the spaces between 120 the rocking bars and having cap portions resting against the curved surface of said rocking bars.

8. A furnace-grate surface, comprising carrier-bars having journal-bearings in their upper edges, rocking grate-bars journaled in said bearings and having fuel-supporting caps provided with curved edges, and filler-bars mounted between said journaled bars, the said filler-bars having movable caps resting 130

6 by gravity against the curved surface of the rocking bar.

9. A stoking-grate surface comprising carrier-bars, rocking grate-bars journaled thereon, intermediate bars having fixed portions secured to the carrier-bars and cap portions pivotally mounted on the supporting portions of said fixed portions and each resting at one edge against the adjacent edge of a rocking bar for preventing the running through of fuels at the meeting edges of the bars.

10. A fuel-stoking-grate surface, for furnaces comprising a plurality of rocking grate-bars, a dead-plate at the upper end of the 15 grate-surface and a filler-bar closing the space between said dead-plate and the upper rocking bar, said filler-bar having a fixed body portion and cap portions pivotally mounted on the supporting portions and extending upwardly therefrom.

11. A stoking-grate mechanism, comprising a fuel-supporting surface formed with rigid portions a plurality of rocking grate-bars, a sealing or filler bar mounted between 25 the upper rocking bar and the adjacent rigid portions of the fuel-supporting surface, said filler-bar being made up of a fixed bar having upwardly-projecting lugs and pivoted caps pivotally secured to said lugs.

12. A stoking-grate surface, comprising a plurality of rocking grate-bars, a space-filling bar at the upper edge of the grate-surface having a fixed lower portion and a movable cap portion pivoted thereto, the said cap portion having recesses in one surface, the said recessed surface resting against the adjacent rocking bar.

13. A stoking-grate surface, comprising a plurality of rocking bars suitably spaced 40 apart, intermediate filler-bars mounted between them having pivoted caps extending therefrom some of said caps extending forward and others rearward from the supporting-bar and engaging the adjacent movable surfaces of the rocking bars.

14. A furnace-stoking-grate surface, comprising a plurality of rocking stoking-bars, intermediate filler-bars having angle-iron fixed 45 base portions and cap portions pivotally mounted on the supporting portions, some of said caps extending toward and others rearward from the supporting-bar against the adjacent rocking grate-bars.

15. An inclined stoking-grate surface, comprising a plurality of rocking stoking-bars, intermediate filler-bars having pivoted fuel supporting caps, the rear cap resting against the next lower rocking bar and the forward cap overhanging the said rear cap and at its 55 forward edge resting against the next forward rocking bar.

16. A stoking-grate surface having rocking grate-bars formed with forwardly-extending fuel-supporting webs, curved tie-plates joining the ends of said webs and intermediate

filler-bars having pivoted portions resting against said curved tie-plates.

17. A stoking-grate surface provided with a plurality of rocking grate-bars having forwardly and rearwardly extending fuel-supporting webs, and intermediate filler-bars having pivoted caps resting against the edges of the rearwardly-extending webs and preventing the running through of fuel at that point.

18. A fuel-stoking-grate surface, comprising a plurality of rocking bars having forwardly and rearwardly extending fuel-supporting webs, the forwardly-extending webs having curved connecting tie-plates, and intermediate filler-bars having forwardly and rearwardly extending cap portions pivotally mounted on the supporting portions, the rearwardly-extending caps engaging the curved tie-plates of the adjacent rocking bar 85 while the forwardly-extending caps engage the edges of the rearwardly-extending webs on the adjacent rocking bar.

19. A stoking-grate mechanism, comprising a plurality of rocking grate-bars having 90 curved front and rear edges, the said curved edges having the axis of movement of the bars for their centers, intermediate filler-bars having front and rear cap portions pivotally mounted in the supporting portions resting 95 against the adjacent curved surfaces of the rocking bars and preventing fuel from running through the spaces between the bars.

20. A stoking-grate surface, comprising rocking grate-bars made up of body portions 100 and overhanging caps the said body portions having elongated sockets formed therein while the said caps are provided with broad tapering shanks extending into said sockets, journals at the ends of the body portions, 105 carrier-bars for engaging said journals and movably supporting the bars, and end caps having end projections reduced in depth so as to overhang the journals and protect the same from the consuming fuel on the grate-surface.

21. A stoking-grate mechanism, comprising adjacent grate-sections, carrier-bars supporting the same, some of said bars arranged between the grate-sections and having 115 curved apertures formed therein, said grate-sections comprising oppositely arranged rocking bars in each section, and arms rigidly mounted upon each rocking bar, the rocking bars of one section having a plurality of such 120 arms, while the rocking arms of the adjacent section have only a single arm, pins rigidly secured to said bars and passing through the curved apertures in the carrier-bars for tying the rocking bars together, and means for 125 driving one section, the connecting-pins causing the bars of the adjacent section to be also rocked therewith.

22. A stoking-grate mechanism, comprising a fuel supporting and stoking surface 130

made up of a plurality of rocking grate-bars, 5
filler-bars sealing the spaces between them
for forming a continuous surface, arms con-
nected with the rocking bars for rocking
them and means mounted adjacent to the
furnace-front for imparting the same or a
differential movement to the said bars.

23. A stoking-grate mechanism, comprising
carrier-bars, movable grate-bars jour-
naled thereon, filler-bars contacting with
said grate-bars for sealing the spaces between
the movable bars, means connecting the
movable bars with a feeding mechanism
mounted adjacent to the furnace-front, and
means for imparting the movement of the
bars from one grate-section to those of the
adjacent grate-section.

24. A stoking-grate surface comprising a
plurality of grate-sections, and carrier-bars
for supporting each grate-section, said car- 20
rier-bars being provided with apertures
therein; said grate-sections comprising rock-
ing-bars, projecting arms secured to each
rocking bar, and connecting-pins extending
through said apertures in the carrier-bars for 25
connecting the bars on the corresponding
rocking bars to adjacent grate-sections, for
securing a simultaneous movement thereof.

In testimony whereof I affix my signature
in presence of two witnesses.

WILLIAM McCLAVE.
